UNITED STATES PATENT OFFICE.

GEORGE B. McFARLAND, OF COLUMBUS, NEBRASKA, ASSIGNOR OF ONE-HALF TO W. IRVING SPEICE, OF COLUMBUS, NEBRASKA.

FLOUR-BLEACHING APPARATUS.

No. 878,738.

Specification of Letters Patent.

Patented Feb. 11, 1908.

Application filed July 2, 1907. Serial No. 381,914.

To all whom it may concern:

Be it known that I, GEORGE B. McFARLAND, of Columbus, in the county of Platte and in the State of Nebraska, have invented 5 a certain new and useful Improvement in Flour-Bleaching Apparatus, and do hereby declare that the following is a full, clear, and exact description thereof, reference being had to the accompanying drawing in which the 10 figure is a vertical section of an apparatus for bleaching flour embodying my invention.

The object of my invention is to provide a simple and inexpensive apparatus for bleaching flour by the agency of peroxid of nitrogen, and to this end my invention consists in the flour bleaching apparatus constructed substantially as hereinafter specified and claimed.

In the embodiment of my invention as 20 illustrated in the drawing, I employ a suitable framework 1, which may be made of wood, which in its upper parts supports a generator 2 of peroxid of nitrogen gas, which generator comprises a simple tank of glass 25 or aluminium containing nitric acid and a metal such as galvanized iron. From the top of the generator, a pipe 3 is carried to the top of a tank 4 beneath the generator and supported on the bottom of the framework 30 into which tank 4 flows gas as fast as it is generated in the generator. In the tank 4 is placed a volume of water, and from a point near the bottom of the tank 4 a vertical pipe 5^a leads to a water-receiving tank 5 supported on the top of the framework, the water 35 being forced by the pressure of the gas from the tank 4 up into the tank 5. To permit the removal of the cover of the generator 2 when necessary, without any loss of gas from the 40 tank 4, a check valve 6 is provided in the pipe 3, which will prevent the backward passage or egress of gas through the pipe 3. The cover or generator 2, of course, is applied thereto in a gas-tight manner, as by means 45 of a clamp and a rubber washer, and the cover of the tank 4 is also secured thereto in a gas-tight manner, but the cover of the tank 5 may be a loose one.

From the top or cover of the tank 4 a gas 50 eduction pipe 7 leads to the upper end of a vertical chamber 8, through which the flour to be bleached is passed, and to which it is delivered from a chute 9. The chamber 8 is

a mixing chamber to produce the thorough commingling or mixing of the flour and 55 gas, and to effect this, one or more rotatable fans 10 are placed in said chamber, one being situated above the gas eduction pipe 7 and by which its pivot is supported, the end of the pipe being carried to the center of the 60 chamber, and turned downward. The wings or vanes of the fan are so shaped and inclined that the impact of the descending flour upon them will cause the fan to revolve, scattering the flour by centrifugal force and producing 65 a downward current of air through the chamber. The flour being scattered or separated into a dust is in condition for access of gas throughout its mass or volume, so that a most perfect mixing or commingling of the 70 gas and flour is secured. Such other fans as may be used are below the eduction pipe in the mixing chamber, and they operate in the same manner to scatter the flour and thoroughly mix it with the gas and air. Preferably the mixing chamber is considerably 75 larger in diameter than the flour inlet thereto, and the diameter of the fans is just sufficiently less than the internal diameter of the mixing chamber to cause the fans to clear 80 the inside walls of the chamber. The top of the hub of the fans is surmounted by or formed into a pointed or conical projection 11 to prevent the lodgment of flour. The flow of gas into the mixing chamber is regulated by a needle or other valve 12.

In the use of my apparatus, enough gas is generated, say, for one day at the mill, the gas as fast as it is generated passing into the tank 4, and its pressure being utilized by 90 driving water from the tank 4 up into the elevated tank 5, so that in this way the pressure of the gas is stored up and is utilized to force the gas from the tank 4 into the flour passage or chute. In the particular that I 95 utilize the pressure of the gas as it is generated to force the gas from the storage tank 4 to the flour chute, my invention differs radically from apparatuses prior to mine, in which fans or blowers have been necessary 100 to force the treating gas into the flour to be treated.

When more than one fan is used, as shown in the drawing, the alternate fans have their wings or vanes arranged so that alternate 105 fans revolve in opposite directions to pro-

duce a greater agitation or scattering of the flour than would be the case were the fans all arranged to rotate in the same direction.

Having thus described my invention, 5 what I claim is:

1. In flour bleaching apparatus, the combination of a gas generator, a gas tank in communication with the generator, an elevated liquid-holding tank in communication 10 with said gas tank into which liquid is forced by the pressure of gas from the generator entering the gas tank, and means for the delivery of gas leading from the gas tank to the flour to be treated.
- 15 2. In flour bleaching apparatus, the combination of a gas generator, a gas tank in communication with the generator, an elevated liquid-holding tank in communication with said gas tank into which liquid is forced 20 by the pressure of gas from the generator entering the gas tank, a vertical chamber provided with agitating means, through which flour to be treated passes, and a pipe leading from the gas tank to said chute.
- 25 3. In flour bleaching apparatus, the combination of a gas generator, a gas and liquid-holding tank in communication with the generator, an elevated liquid-holding tank, a pipe leading from one tank to the other, 30 so that liquid may be forced from the gas-

holding tank, by the pressure of gas, into the elevated tank, and may descend from the latter into the gas-holding tank, to supply pressure to expel gas therefrom, and means for the delivery of gas from the gas 35 tank to the flour to be treated.

4. In flour bleaching apparatus, the combination of a gas generator, a gas and liquid holding tank, to the upper part of which a pipe leads from the generator, an elevated 40 liquid-holding pipe, a pipe leading from the gas and liquid holding tank to the bottom of the elevated tank, through which liquid passes from one tank to the other, and a pipe leading from the upper part of the gas and 45 liquid holding tank to the flour to be treated.

5. In flour bleaching apparatus, the combination of a source of supply of gas, a chamber for the passage of flour, means for supplying gas to such chamber, and a series of 50 oppositely rotatable flour-agitating devices in the path of flour passing from the chamber, alternate ones of said devices being oppositely rotatable.

In testimony that I claim the foregoing I 55 have hereunto set my hand.

GEORGE B. McFARLAND.
